UNITED STATES PATENT OFFICE.

BENJAMIN FLEIGEL, OF BOSTON, MASSACHUSETTS.

SEWING-MACHINE ATTACHMENT.

No. 831,334.

Specification of Letters Patent.

Patented Sept. 18, 1906.

Application filed February 12, 1906. Serial No. 300,610.

To all whom it may concern:

Be it known that I, BENJAMIN FLEIGEL, a citizen of the United States, residing in Boston, county of Suffolk, and State of Massachusetts, have invented an Improvement in Sewing-Machine Attachments, of which the following description, in connection with the accompanying drawings, is a specification, like characters on the drawings representing like parts.

This invention, relating to sewing-machine attachments, is herein represented as embodied in that class of attachments designated as an edge-gage; but the features of invention to be hereinafter designated may be employed with advantage with other forms of attachments—as, for instance, braiders, corders, hemmers, and the like.

In the manufacture of clothing where work, such as coats, is given out to workmen in quantities to be finished by the piece it is necessary frequently to make parallel lines of stitching in the cloth at different distances from its edge, and as edge-gages are now commonly made and used for edge-stitching if each garment is completed before commencing the edge-stitching of a second garment the operator has to adjust the edge-gage prior to each stitching operation and to make it certain that the position of the gage in its new adjustment is correct. He has after each adjustment and before commencing regular stitching to make some trial stitching to ascertain that the adjustment of the gage is just right to insure uniformity in the spacing of the edge-stitching, so that the whole lot of garments shall be stitched just alike. Very much time is lost in making these different adjustments, and even then the stitching on ten or twenty coats made in succession is liable, due to haste or carelessness in making the adjustments, to vary and render the work unsatisfactory to the merchant for whom the clothing was made.

I have made an attachment having a plurality of edge-gages, either of which may be set with relation to the needle to insure the making of lines of stitching at either of two distances from the edge of the garment, and while one gage occupies its operative position and receives against it the edge of the garment the other gage may and will be inoperative. Either of these gages may be instantly put into its inoperative position, according to which one of the gages it is desired to use. The two gages are mounted on an attaching-plate, and

by so supporting said gages that either may be used at will without any care as to adjusting the same with relation to the needle when making either line of stitching first-class work may be done, and a number of coats or garments may be stitched just alike without any possibility of error after the gages have been once set for the particular work to be done. By the use of my improved gage an operator may turn out in the same time very much more work than with usual edge-gages and may do the work more uniformly, as it is almost impossible to set a gage prior to making each line of stitching in exactly the same spot, and especially so where, owing to the small pay of the operator, but little time can be spared for the adjustment of a gage to even approximate accuracy.

In accordance with my invention I have connected with an attaching-plate two holders, each provided with an edge-gage, and when parallel lines of stitching are to be made in succession one gage may be brought into its operative position for use and when it has been used it may be put into its inoperative position and the other gage may occupy its operative position. Either edge-gage may be put into its operative position whenever desired, or one or both gages may be put into their inoperative positions, leaving free space in which the operator may handle the work.

Figure 1 in the drawings represents an attachment embodying my invention, one of the gages receiving against it the edge of the work to be stitched. The dotted lines show both gages in their inoperative positions. Fig. 2 shows in its inoperative position the gage that is shown in Fig. 1 as operative. Fig. 3 is a section enlarged in the line *x*, Fig. 1.

The attaching-plate *A* has a hole through which and into a threaded hole in the work-plate *B* is extended the threaded shank of a thumb-screw *a*, by which to fix the attaching-plate to the work-plate. The attaching-plate receives two stud-screws *c d*, the former acting as a pivotal connection for the holder *C* and the latter for the holder *D*.

The holders *C* and *D* are each bored longitudinally for the reception of the shanks *c' d'* of the two edge-gages *c² d²*, each shank having coacting with it a suitable screw, as *c³* or *d³*, to maintain the edge-gages in any position in which they may be adjusted according to the work to be done.

The holder *D* at the farther side of the at-

taching-plate is shown as adapted to be locked in its operative position by a locking device comprising a spring-plate 2, represented as riveted at 4, near one side to the attaching-plate and having a lip 5 to engage an edge 6 of said holder. When it is desired to put the holder D in its inoperative position, the button 7 of the spring-plate 2 will be depressed or moved downwardly to disengage the plate from the edge 6 and thereafter a spring 8, (shown only in Fig. 2,) connected at one end with the attaching-plate and interposed between said plate and holder D, will be released from its compressed state and will expand and move the holder D automatically from its operative position with relation to the attaching-plate that it may be turned aside, as shown in Fig. 1.

The presser-foot F is and may be of any usual construction, and the needle of the sewing-machine penetrates the cloth at the point (indicated by 10) close to the inner edge 12 of the presser-foot. The drawing, Fig. 1, shows the edge-gage c² in its operative position, and it will be readily understood that the holder C may be moved about its pivot into the dotted-line position, which would leave the gage d² in operative position. (See Fig. 2.) When the gage c² is used, the stitching is nearer the edge of the coat or work than when the gage d² is used.

Having fully described my invention, what I claim as new, and desire to secure by Letters Patent, is—

35 1. An attachment for sewing-machines, an attaching-plate, means for securing it to the work-plate of the machine, a plurality of separate gage-holders, each independently

pivoted to said attaching-plate to swing in a plane parallel thereto, and gages adjustably mounted within said holders to act upon the material being stitched to insure parallel relation of successively-formed lines of stitches. 40

2. In an attachment for sewing-machines, an attaching-plate, means for securing it to the work-plate of the machine, a plurality of holders pivotally mounted independent of each other for separate adjustments in a plane parallel to the work-plate, said holders having a fixed relation near one end of said attaching-plate, and each of said holders having an end gage, independently adjustable longitudinally of its holder to act upon the material being stitched to insure parallel relation of successively-formed lines of 55 stitches. 45

3. In a sewing-machine attachment, an attaching-plate, a plurality of connected edge-gages capable each of separate adjustment in the plane parallel to the bed-plate 60 that their acting edges may occupy different positions with relation to the line of stitching, either gage being adapted to be moved into its inoperative position while the other gage occupies its operative position to insure parallel relation of successively-formed lines of 65 stitches and means for automatically placing one of said gages in its inoperative position. 50

In testimony whereof I have signed my name to this specification in the presence of 70 two subscribing witnesses.

BENJAMIN FLEIGEL.
